UNITED STATES PATENT OFFICE.

BENJAMIN W. JOHNSON, OF CRAFTON, PENNSYLVANIA.

LATCHES FOR DOUBLE DOORS.

1,013,553.

Specification of Letters Patent.

Patented Jan. 2, 1912.

Application filed January 13, 1911. Serial No. 602,492.

To all whom it may concern:

Be it known that I, BENJAMIN W. JOHNSON, a citizen of the United States, resident of Crafton, in the county of Allegheny and 5 State of Pennsylvania, have invented a new and useful Improvement in Latches for Double Doors; and I do hereby declare the following to be a full, clear, and exact description thereof.

10 My invention relates to locks for double doors of cupboards, closets, windows, etc.

The object of my invention is to provide a simple form of locking device by means of which each door of a pair may be latched 15 independently of each other, and at the same time provide for the positive locking of one of the doors when the second door is closed and latched; and to these ends my invention comprises the novel features hereinafter set forth and claimed.

Referring to the accompanying drawings Figure 1 is a front view of a cupboard partly broken away with my invention applied thereto; Fig. 2 is an enlarged section 25 on the line 2—2 Fig. 1; Fig. 3 is a like view to Fig. 2 showing the parts in different position; and Fig. 4 is a section on the line 4—4 Fig. 2.

I have illustrated my invention in connection with a simple form of cupboard or 30 closet in which the two doors 2 and 3 are in close relation with each other at the closing edges, and secured to the frame 4 is the shell or casing 5 which is held in place by means 35 of the screws 6. Within the casing 5 is the guide-way 7 formed by the metal-plate 8. Within the guide-way 7 are the latches 9 and 10. The latch 9 is secured to the bar 11 and the opposite end of said bar passes 40 through an opening 12 in the latch 10. A spring 13 encircles the bar 11 and said spring bears against the inner face of the latch 9 and the inner face of the latch 10. Stops 14 and 15 limit the outward movement 45 of the latches 9 and 10. The latch 10 has the tail-piece 16 which acts as a guide for the latch 10 within the guide-way 7 of the casing.

Secured to the door 2 is the catch 17 with 50 the notch 18 and a like catch 19 is secured to the door 3. When the door 2 is closed the catch 17 will slip by the latch 10 and the spring 13 will then act to force the latch

into the notch 18 and the door 2 while not locked is latched so that it will not open 55 without applying a pulling force to overcome the action of the latch 10. In like manner the door 3 may be closed and latched by the latch 9. However, the latching of the door 3, in the present form of 60 my invention, also acts to positively lock the door 2, for the movement of the latch 9 by the catch 19 will act to move the bolt-rod 11 which is secured to the latch 9 to the left, and the end of said bolt-rod will enter the 65 notch 18 of the catch 17 and thus positively lock the door 2, so that the door 2 cannot be opened without first opening the door 3. However, if desired I may dispense with the positive locking of the door 2 by shortening 70 the bolt-rod 11 so that it will not engage the notch 18 of the catch 17, and in that case the closing of each door will simply latch each door, so that they can be opened independently of each other. In some cases 75 where it is not found necessary to lock the door sections this construction in which the positive lock is omitted will be found desirable, and I provide a double latch in which the door sections are latched entirely independently of each other. 80

It is apparent that my invention may be applied to numerous forms of double doors, and the location of the device may be varied to suit different conditions, as in some cases 85 it may be desirable to locate it at the bottom instead of the top of the door or window frame, and in some cases the doors may be separated by an intervening strip, all of which different modes of application are 90 included within my invention.

What I claim is:

1. In a fastener for double doors, the combination with a suitable casing adapted to be located in the door frame, of a pair of 95 latches therein movable longitudinally in opposite directions to latch and unlatch, a catch adapted to be applied to each door section to engage one of said latches, and means coöperating with said latches and 100 catches whereby the door last closed will cause the door first closed to be positively locked.

2. In a fastening for double doors, the combination with a suitable casing adapted 105 to be located in the door frame, of a pair of

latches therein, a catch adapted to be applied to each door section to engage one of said latches, a bolt rod secured to one of said latches, said latch being movable by the 5 catch of the door last closed to cause the bolt rod to engage the catch of the door first closed to positively lock the latter door.

In testimony whereof, I the said BENJAMIN W. JOHNSON have hereunto set my hand.

BENJAMIN W. JOHNSON.
